UNITED STATES PATENT OFFICE.

GEORG MICHAEL PFAFF, OF KAISERSLAUTERN, GERMANY.

SCREW-THREADING MACHINE.

SPECIFICATION forming part of Letters Patent No. 727,194, dated May 5, 1903.

Application filed June 1, 1901. Serial No. 62,736. (No model.)

To all whom it may concern:

Be it known that I, GEORG MICHAEL PFAFF, a subject of the King of Bavaria, residing in the city of Kaiserslautern, Kingdom of Bavaria, German Empire, have invented certain new and useful Improvements in Screw-Threading Machines, of which the following is a specification.

This invention relates to screw-threading machines for making male threads, and has for its object to remedy the objections found in the hitherto-employed threading devices—viz., that the catches which serve to release the dies intermittently engage with each other, even after the thread has been cut to the desired length. This is due to the fact that the dies remaining in engagement with the finished screw-bolt revolve with the latter because the rotatory movement of the screw-bolt cannot be at once stopped owing to the centrifugal power of the revolving parts of the machine. In consequence of this intermittent engagement of the catches with each other the dies continue to thread the bolt above the desired length, so that the work is improperly done, and frequently the head of the screw-bolt is broken off. Further, the catches wear off very quickly, and the whole machine suffers dangerous shocks. Much trouble is also experienced in removing the bolt from within the dies, particularly when the latter are made of a single piece. In the present invention this objection is removed by the arrangement of yielding catches, which after the thread has been cut to the desired length and when the longitudinal movement of the dies has changed to rotation do not interfere with each other when coming into engagement.

In the accompanying drawings, Figure 1 is a side elevation of a screw-threading machine to which my improvement is applied. Fig. 2 is a longitudinal section of the die-holder, the latter being in the position shortly before the threading operation begins. Fig. 3 is a similar partial section, the die-holder being in position at the moment of release of the dies, at which the catches intermittently touch each other. Fig. 4 is a cross-section on line I I, Fig. 2. Fig. 5 is a cross-section on line II II, Fig. 2, as seen in the direction of arrow III;

and Fig. 6 a similar section as seen in the direction of arrow IV.

The new cutting or threading device is provided with one or several catches, consisting of a pin *n*, having a head *i* and secured to the die-holding head *b* by means of a set-screw *k*. A cap *l* under the influence of a coiled spring *m*, which has the tension to press the cap outward, embraces the pin *n*. This cap is held against escapement from above the pin *n* by means of a shoulder *o* resting upon the head *i* of the pin. The cap *l* normally projects beyond the head *i* and is provided with a beveled edge *h*. The spindle *p* of the head *b* is guided in a casing *q*, having a head *r*. This casing is, as seen in Fig. 1, secured in a boring of the support *t* of the screw-machine, so as not to be movable therein. The spindle *p* of the head *b*, carrying the dies, is adapted to move longitudinally within the casing *q* and can rotate therein in one direction only—*i. e.*, in the direction of the rotatory movement of the threaded bolt. It is prevented from rotating in the reverse direction by a pin *u*, mounted on a spring *v* in a boring *w* of the spindle *p*. As shown in Fig. 4, this pin is beveled and projects under the influence of the spring *v* into a correspondingly-shaped groove of the casing *q*, thus allowing a rotation of the spindle in the direction mentioned above. In the head *r* of the casing *q* is arranged a catch, consisting of a pin *g*, that rests with its back upon a leaf-spring *f*, attached to head *r*.

The operation is as follows: The threading device is advanced toward the work to be cut by means of the support *t* until the dies engage the work which is revolving. At this moment the threading operation begins, and while the work rotates, the dies, together with the head *b* and its spindle *p*, are moved forward until the desired length of the thread has been cut. The position of the catches with regard to each other at the end of the threading operation is illustrated in Fig. 3. As the finished work cannot be at once stopped or reversed in order to release the dies owing to the momentum of the revolving parts of the machine, and as the dies are still in engagement with the finished work, the dies begin to rotate with this work, the pins *g*

having cleared the caps *l*. The consequence is that the catches of the head *b* and those of the head *r* will intermittently touch each other, but being yielding, as above described, 5 will give way and will have no effect upon the rotating dies—that is to say, will not cause a further threading of the work. In the meantime the revolving parts as well as the work will be reversed, and as the spindle 10 *p* is not allowed by the pin *u* to rotate in the reverse direction the dies will be caused to screw off the work and return to their initial position.

The length of the outwardly-projecting 15 parts of the catches corresponds to the length of the thread to be cut, different lengths of the thread requiring catches of different lengths.

What I claim is—

1. In a screw-threading machine, the combination of a rotatable die-holding head with 20 a pin projecting therefrom, a slideable spring-influenced cap having a beveled edge and

projecting beyond the pin, means for holding the cap to the pin, a fixed head, and a pin projecting from said head into the path of 25 the beveled cap, substantially as specified.

2. In a screw-threading machine, the combination of a rotatable die-holding head with a pin projecting therefrom, a slideable spring-influenced cap having a beveled edge and 30 projecting beyond the pin, means for holding the cap to the pin, a fixed head having a perforation, and a spring-influenced pin engaging said perforation and arranged within the path of the beveled cap, substantially as 35 specified.

In witness whereof I have hereunto signed my name in the presence of two subscribing witnesses.

GEORG MICHAEL PFAFF.
